UNITED STATES PATENT OFFICE.

MARA H. MOORMAN, OF LYNCHBURG, VIRGINIA.

SEPARABLE RIGID HEAD-AND-SOCKET FASTENER.

1,251,085.

Specification of Letters Patent.

Patented Dec. 25, 1917.

Application filed November 9, 1914. Serial No. 871,020.

To all whom it may concern:

Be it known that I, MARA H. MOORMAN, a citizen of the United States, residing at Lynchburg, in the county of Campbell and 5 State of Virginia, have invented certain new and useful Improvements in Separable Rigid Head-and-Socket Fasteners, of which the following is a specification.

This invention relates to buckles, buttons, 10 and clasps, and more specifically to separable rigid-head-and-socket fasteners.

The object of my invention is to provide a rigid-head-and-socket fastener which is simple in construction, durable, and effective in operation. My invention is designed primarily for use as a shoe fastening device, for which purpose substantial parts are required, without delicate springs of any kind to wear out. This button may be readily 20 fastened and unfastened with the fingers, and is so constructed that it will not come open unless forced open by a pull with the fingers such as is used in the operation of opening an ordinary button shoe.

25 Other objects of this invention not at this time more particularly enumerated, will be clearly understood from the detailed description and drawings forming a part of this specification.

30 Furthermore, this invention consists in the novel arrangement and combination of parts more particularly described in the following specification and embodied in the claim appended hereunto and forming a part 35 of this application.

Referring now to the drawings which are merely illustrative of my invention, Figure 1 is a longitudinal sectional view of my device in closed position, taken on the line 40 1-1 of Fig. 2, while Fig. 2 is a horizontal sectional view of the same taken on the line 2-2 of Fig. 1. Fig. 3 is a transverse sectional view taken on the line 3-3 of Fig. 2. Fig. 4 is a detail view of the button or head 45 member of my device. Fig. 5 is a detail plan view of the buttonhole plate of my socket, while Fig. 6 is a modification of the same.

Referring further to the drawings, where- 50 in similar reference characters designate similar parts throughout the respective views, 1 designates a hollow metal cap, one side of which is oval while the opposite side is flat. A key-hole slot is formed in the 55 frame side of the cap 1 including a substantially circular hole 2, and a tongue-shaped

slot 3 which is radial to said hole 2 and formed in continuation thereof, are punched through the flat face of said cap 1 in such manner as to leave a flap on the side of said hole opposite said slot, so that one end of the cut portion may be bent upwardly within the slot to form a spring 4. Integral with the flat side of said cap, projecting therefrom, and spaced apart around the circumference 60 thereof are a plurality of pronged members 5 adapted to serve as a means for fastening said cap to the member 6 which is to be fastened. A button consisting of a circular head 7 slightly flattened on its top, 65 a shank 8 integral therewith, and a base plate 9 integral with the outer end of said shank is adapted to be secured, by means of pronged members 10 spaced apart around said base plate, to the member 11 which is 70 to be fastened to the member 6 to which the socket is secured.

A modification of my cap provides a double, or split, spring 4^a as shown in Fig. 6, but it will be apparent that in each of the 80 illustrated forms the spring 4 will engage with the button head as the latter is forced toward the hole 2, thus resisting to a desired degree the withdrawal of the button head. The spring 4 does not, however, contact 85 with the head 7 except at the withdrawal or entrance thereof from the fastener 1, so that this spring need not be subjected to undue tension.

The utility, adaptability, and advantages 90 of my improved form of separable rigid-head-and-socket fasteners being obviously apparent, it is unnecessary to further enlarge upon the same herein.

Having now described and pointed out 95 the new and useful features of my invention, I do not limit myself to the shape of certain parts where the shape is not essential, nor do I restrict myself to the exact details of construction shown and described, but mean 100 and intend to claim all equivalents and variations thereof not departing in principle from my invention and falling within the purview of the appended claim.

What I claim is my invention and desire 105 to secure by Letters Patent is:

In a device of the class described the combination of a pair of superposed strips, a headed stud having a base plate secured to the lower strip, the upper strip having a 110 circular stud receiving opening and a projecting shank receiving slot, a hollow cap

having an integral flat base secured to the upper surface of the upper strip above said openings, said base having complementally arranged openings therein alining with the 5 openings in the strip, and an integral ar-

cuate spring tongue projecting from the edge of the circular opening in said base at a point diametrically opposite the slot and extending between said edge and the

adjacent top of the cap in substantially the 10 same arc as the curvature of the contiguous edge of said cap.

In testimony whereof I affix my signature in presence of two witnesses.

MARA H. MOORMAN.

Witnesses:

GILES H. MILLER,
O. E. JONES.
